CLAIM

The ornamental design for a cooling system enclosure, as
shown and described.

DESCRIPTION

FIG. 1 is a front left perspective view of the cooling system
enclosure design.

FIG. 2 is a bottom right perspective view of the cooling
system enclosure design.

FIG. 3 is a front view of the cooling system enclosure
design.

FIG. 4 is a rear view of the cooling system enclosure design.

FIG. 5 is a right side view of the cooling system enclosure
design.

FIG. 6 is a left side view of the cooling system enclosure
design.

FIG. 7 is a top view of the cooling system enclosure design;
and,

FIG. 8 is a bottom view of the cooling system enclosure
design.

The broken lines shown in FIGS. 1-8 represent portions of
the cooling system enclosure design that form no part of the
claim.
